UNITED STATES PATENT OFFICE.

CHARLES M. GREEN, OF LYNN, MASSACHUSETTS, ASSIGNOR TO GENERAL ELECTRIC COMPANY, A CORPORATION OF NEW YORK.

DYNAMO-ELECTRIC MACHINE.

No. 905,512.

Specification of Letters Patent.

Patented Dec. 1, 1908.

Application filed August 12, 1903. Serial No. 169,176.

To all whom it may concern:

Be it known that I, CHARLES M. GREEN, a citizen of the United States, residing at Lynn, county of Essex, State of Massachusetts, have invented certain new and useful Improvements in Dynamo-Electric Machines, of which the following is a specification.

The object of my present invention is to improve the construction of dynamo-electric machines.

More particularly my invention relates to constant current generators of the well-known type called Brush machines or Brush arc light machines, though all of the features of my invention are not limited to such machines.

My invention consists in certain novel features of construction and arrangement which will be pointed out in the claims annexed to and forming a part of this specification.

For a better understanding of my invention reference may be had to the accompanying drawings in which I have illustrated one embodiment of my invention:

Of the drawings Figure 1 is a perspective view of a dynamo-electric machine in which my invention is embodied; Fig. 2 is a sectional elevation of the armature; Fig. 3 is an elevation showing details of the armature and shield; Fig. 4 is a developed view of the armature shield; Fig. 5 is a section taken on line 6—6 of Fig. 4; and Fig. 6 is a view showing the way in which the material for the shield is cut from stock.

In the particular form of my invention which I have illustrated in the drawings, I have shown a dynamo-electric machine known as the Brush machine.

Referring to the drawings, 1 represents a base of suitable construction on which the generator frame 2 proper is adjustably mounted. Bearing blocks 5 and 6 carried by end portions 3 and 4 of the frame 2 support suitable bearings in which the tubular shaft 7 is mounted. This shaft carries at one end suitable commutator members 8 and at the other end a power-receiving pulley 9. The shaft also carries intermediate its ends an armature 10 which revolves between pole pieces 11 which project inwardly from the upper extensions 3 and 4 of the frame 2.

I make no claim in the present application

to the construction of the pole pieces. These 55 pole pieces form the subject matter of an application Serial No. 231,849, filed by me on the 8th day of November, 1904, as a division of this application.

The armature 10 comprises a ring 12 formed of laminated magnetic material provided at intervals with laterally projecting portions 13 of magnetic material. The laterally projecting portions 13 are formed of pieces or laminae of magnetic material which are interleaved with the laminae composing the ring as is shown in Fig. 2. The two sets of laminae are secured together in any suitable manner. The ring is supported by arms 14 which are carried by a hub 15 mounted on 70 the shaft 7. Bolts 16 secure the ring to the ends of the arms 14. Coils 17 surround the ring portion, one coil being located between each adjacent pair of projecting portions. The outer ends of these coils project beyond 75 the outer periphery of the ring portion and are usually curved as clearly shown in Figs. 2 and 3. By reason of the irregular outline thus presented, the air resistance to the rotation of the armature is considerable. To 80 reduce this resistance I have surrounded the armature by a shield or guard 18. This shield is preferably formed of fabric such as duck and is made up of several sections 19 which are connected by seam lines 20 as indicated in Fig. 4. The material out of which the guard or shield is made is cut on the bias preferably at an angle of 45° to the direction of the threads as indicated in Fig. 6 where 19' represents a strip of stock from 90 which sections 19 are cut. The edges of the guard are folded back and secured to the body of the guard in any suitable manner as by a line of stitching 21 in such manner as to leave pockets or channels 22 at each 95 side of the guard in each of which cords 23 are placed, see Figs. 4 and 5. When the guard or shield is placed upon the armature the ends of the cords 23 are drawn tightly together and connected. This makes the 100 edges of the shield shorter than the body and pulls the guard or shield into the shape clearly shown in Figs. 1, 2 and 3, in which the shield closely embraces the curved ends of the coils. By reason of the manner in 105 which the canvas is cut, the shield will be stretched perfectly taut. With the smooth outer surface obtained under these circum-

stances the air causes considerably less resistance to the motion of the machinery when it is rotated at a high speed than when the shield is omitted. The ends of the strip forming the shield may be secured together before or after the edges of the shield are drawn into place. The spaces left between the coils insure a good ventilation of the armature. In practice I prefer to size and 10 shellac the shield after it is placed in position.

I have chosen to illustrate my invention in connection with the armature of a Brush machine, but it is evident to those skilled in 15 the art that my invention may be applied to any member of any type of dynamo-electric machine, and I aim in the appended claims to cover all modifications which do not depart from the spirit of my invention.

20 What I claim as new and desire to secure by Letters Patent of the United States, is,

1. In a dynamo-electric machine, an armature having an irregular outline, and a self-contained shield therefor made of a strip 25 of flexible woven fabric and means carried by the fabric for causing the shield to closely embrace the armature.

2. In a dynamo-electric machine, an armature having an irregular outline, a shield 30 therefor in the form of a strip of flexible material surrounding said armature, and means for shortening the edges of said strip

to cause said strip to tightly embrace the armature.

3. In a dynamo-electric machine, an armature and a strip of flexible material having 35 pockets formed in its edges, and puckering strings located in said pockets by means of which the edges of the strip can be made shorter than the body of the strip and the 40 strip can be caused to closely embrace the armature.

4. In a dynamo-electric machine, an armature, a shield therefor formed out of a strip 45 of woven fabric cut on the bias, and means for gathering the edges of said strip to cause the strip to closely embrace the armature.

5. In a dynamo-electric machine, a member, a shield therefor formed out of flexible 50 material, and means for gathering the edges of said shield to cause the shield to closely embrace the member.

6. In a dynamo-electric machine, a member, a shield therefor formed out of woven 55 fabric cut on the bias, and means for gathering the edges of said shield to cause the shield to closely embrace said member.

In witness whereof, I have hereunto set my hand this seventh day of August, 1903.

CHARLES M. GREEN.
